Kenyon & Kenyon

UNITED STATES PATENT OFFICE

MAURICE M. BALSAM, OF BROOKLYN, NEW YORK

METAL BINDING MACHINE

Application filed March 14, 1928. Serial No. 261,483.

This invention relates to metal-binding machines and more particularly to a machine for attaching metallic binding elements to the corners or edges of pocketbooks or the like.

An object of this invention is an improved, efficient and inexpensive machine of this character which securely fastens the binding element quickly and expeditiously.

10 Other objects, novel features and advantages of this invention will be apparent from the following specification and accompanying drawings, wherein

Fig. 1 is a plan view of the machine;

15 Fig. 2 is a front elevation thereof;

Fig. 3 is a section on the line 3—3 of Fig. 1, with the parts in inoperative position;

1, with the parts in operative position;

Fig. 4 is a view similar to Fig. 3, with the parts in operative position;

20 Fig. 5 is a section on the line 5—5 of Fig.

3; and

Figs. 6 and 7 are detail views.

The machine comprises a bed 10 which may be fastened to a workbench or other support.

25 A block 11 is attached to the plate 10 by bolts 12. This block is substantially rectangular in cross-section and is provided at one end with a V-shaped recess 13. The block 11 is also provided with bores in which are

30 slidably arranged the rods 14. These rods carry at their upper end a plate 16. Interposed between the block 11 and the plate 16 are a plurality of springs 17 which tend to keep the plate 16 out of contact with the

35 block 11.

A bolt 18 passing through the plate 16 and threaded into the block 11 limits the movement of the plate 16 under the influence of the springs 17. A yoke 19 has its legs pass-

40 ing through apertures in the frame 10, the ends of the legs being attached to the plate 16 by means of bolts 20. An operating rod 21 is screwed into the bow of the yoke and provides means whereby a pull may be ex-

45 ereted on the yoke 19 to move the plate 16 towards the block 11.

By means of the bolt 22, a pressure head 23 is attached to the plate 16. This pressure head is shaped to fit into the groove 13 in the

50 end of the block 11 and is designed to slide

up and down in this groove. A pressure foot 24 is carried by the head 23 and is also shaped to conform to the groove 13. The pressure foot is provided with an upstanding lug 25 fitting into a slot in the head 23. A bolt 26 carried by the head 23 has its end extending into a groove provided in the lug 25 to attach the pressure foot to the head and at the same time permit slight pivotal movement of the former relative to the latter.

60 A resilient member 27 is carried by the plate 16 and comprises a resilient piece of steel which is arranged obliquely to the direction of movement of the plate 16 and slants downwardly toward the block 11. It is adjustably attached to the plate 16 by bolts 28 passing through slots in the upper end of the member 27 and threaded into the plate 16. Vertical adjustment of the member 27 is accomplished by means of the adjusting screw 29. At the lower end of the member 27, there is provided a friction strip 30.

65 Gage elements 31 are provided for effecting the proper positioning of an article to be operated upon with respect to the other elements 75 of the machine. That portion 32 of the plate 10 which is arranged directly below and in line with the pressure foot 24 is made removable so that it may be taken out and polished when such action is required.

70 In the operation of this device, a pocketbook corner 33 or the like with a clip or binding element 34 arranged over the corner is introduced into the machine with the binding element resting on the inner end of the removable portion 32 and in contact with the walls of the groove 13. The yoke 19 is then pulled downwardly through the medium of any suitable power applied through the rod 21. This causes the head 23 and the plate 16 to descend, thus bringing the friction member 30 into contact with the pocketbook or other device to the corner of which a binding element is being applied. Due to the slant of the member 27, the friction strip 30 exerts 85 pressure upon the pocketbook to move the same toward the block 11, thereby forcing the edge of the article 33 definitely into contact with the rear interior wall of the binding element as well as pushing the binding 100

element into firm contact with the walls of the groove 13. The pressure foot 24 next comes into contact with the binding element 34 and firmly clamps the same on to the 5 pocketbook corner. The member 27 maintains the article 33 and the clip 34 in immovable relation to the bed 10 while pressure is being applied to the clip. In many instances, the corner clips or binding elements are applied to articles one of the edges of which is 10 of less thickness than the other. In such case, the pressure head 24 pivots slightly about its support so that sufficient pressure is applied both to the thick and the thin part to 15 effect anchoring of the clip to the corner.

A thin metal shield 35 is carried by the plate 16 along its side and rear and depends over the block 11. A plate 36 is attached to the top of the plate 16 by bolts 37. The shield 20 35 and plate 36 cover and protect the working parts and improve the appearance of the machine.

It is apparent, of course, that various structural modifications may be made in the device 25 above described without departing in any way from the spirit of the invention as defined in the appended claims.

1. In a machine for attaching binding clips to the corners of pocketbooks or the like, a 30 bed, a head movable toward and away from said bed, a pressure foot pivotally attached to said head, and means movable with said head for moving toward said pressure foot the article to be operated upon and holding the 35 same while said pressure foot is in its lowered position.

2. In a machine for attaching binding clips to the corners of pocketbooks or the like, a bed, a head movable toward and away from 40 said bed, a pressure foot pivotally attached to said head, and a resilient member movable with said head and slanting toward said pressure foot.

3. In a machine for attaching binding clips to the corners of pocketbooks or the like, a 45 bed, a head movable toward and away from said bed, a pressure foot carried by said head, and a resilient member movable with said head and slanting toward said pressure foot.

4. In a machine for attaching binding clips to the corners of pocketbooks or the like, a bed, a block having a vertical recess in one 50 end, a head mounted for movement along said recess toward and away from said bed, a pressure foot carried by said head, and means movable with said pressure foot to force into the recess an article to be operated upon and hold the same therein.

5. In a machine for attaching binding clips to the corners of pocketbooks or the like, a bed, a block having a recess in one end, a head 60 mounted for movement along said recess toward and away from said head, a pressure foot pivotally carried by said head, and means movable with said pressure foot to

force into said recess an article to be operated upon and hold the same therein.

6. In a machine for attaching binding clips to the corners of pocketbooks or the like, a bed, a block having a recess, a head mounted for movement along said recess toward and away from said bed, a pressure foot carried by said head, and a resilient holding member movable with said head and slanting toward said pressure foot. 70

7. In a machine for attaching binding clips to the corners of pocketbooks or the like, a bed, a block having a recess in one end, a head mounted for movement along said recess toward and away from said bed, a pressure foot pivotally carried by said head, and a resilient holding member movable with said head and slanting toward said pressure foot. 75

8. In a machine for attaching binding clips to the corners of pocketbooks or the like, a bed, a block supported thereby and having a vertical recess in one end, a plate mounted for movement toward and away from said block, resilient means interposed between said block and plate, means for drawing said block toward said bed, a head carried by said plate and movable in said recess, and a pressure foot carried by said head. 80

9. In a machine for attaching binding clips to the corners of pocketbooks or the like, a bed, a block supported thereby and having a vertical recess in one end, a plate mounted for movement toward and away from said block, resilient means interposed between said block and plate, means for drawing said block toward said bed, a head carried by said plate and movable in said recess, and a pressure foot pivotally carried by said head. 90

10. In a machine for attaching binding clips to the corners of pocketbooks or the like, a bed, a block supported thereby and having a vertical recess in one end, a plate mounted for movement toward and away from said block, resilient means interposed between said block and plate, means for drawing said block toward said bed, a head carried by said plate and movable in said recess, a pressure foot carried by said head, and a resilient holding member movable with said head and slanting toward said pressure foot. 100

11. In a machine for attaching binding clips to the corners of pocketbooks or the like, a bed, a block supported thereby and having a vertical recess in one end, a plate mounted for movement toward and away from said block, resilient means interposed between said block and plate, means for drawing said block toward said bed, a head carried by said plate and movable in said recess, a pressure foot pivotally carried by said head, and a resilient holding member movable with said head and slanting toward said pressure foot. 115

12. In a machine for attaching substantially U-shaped binding elements or clips 120

having a pair of walls joined by a bight portion to the edges of a piece of material, comprising a base for supporting the piece of material and the elements to be attached thereto, means for holding the material against relative movement on the base and for advancing the material to dispose and hold the bight portion of the binding element flush with the outer edge of the material, and means movable toward the base for subsequently exerting a pressure against the element or clip to bind the same to the material.

13. In a machine for attaching binding clips to the edges of flexible material, a base for supporting the flexible material, means for holding the clips stationary on the base, means for holding the flexible material on the base and for advancing it so that its edge seats within the clip, and means for clinching the clip upon the edge.

In testimony whereof, I have signed my name to this specification.

MAURICE M. BALSAM.
